UNITED STATES PATENT OFFICE.

MARTIN R. SCHAFER, OF READING, PENNSYLVANIA.

AUXILIARY AIR-INTAKE VALVE.

1,280,310.

Specification of Letters Patent.

Patented Oct. 1, 1918.

Application filed December 20, 1917. Serial No. 208,093.

To all whom it may concern:

Be it known that I, MARTIN R. SCHAFER, a citizen of the United States, residing at Reading, in the county of Berks, State of Pennsylvania, have invented certain new and useful Improvements in Auxiliary Air-Intake Valves; and I do hereby declare the following to be a full, clear, and exact description of the invention, such as will enable others skilled in the art to which it appertains to make and use the same.

This invention is an improvement in internal combustion engines and has particular reference to an auxiliary air valve therefor.

An object of the invention is to provide a valve of simple and inexpensive construction adapted to be mounted in the intake manifold of a combustion engine and connected to the throttle valve rod of the carbureter and controlled thereby to automatically regulate the volume of air entering the intake manifold.

Another object is to provide an improved means for manually controlling the volume of air entering the intake manifold irrespective of the automatic control.

The inventive idea involved is capable of receiving a variety of mechanical expressions one of which, for the purpose of illustrating the invention is shown in the accompanying drawing, wherein:—

Figure 1 is a fragmentary side elevation of an internal combustion engine of a conventional type showing the invention applied thereto.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is an end view of the valve casing with parts removed.

In the drawing the numeral 10 indicates generally an internal combustion engine which may be of any preferred type and which has the usual carbureter 11 connected to the cylinders thereof by means of the intake manifold 12. The carbureter is controlled by the usual throttle valve having the lever 13 to which is connected the adjusting rod 14.

The auxiliary valve which comprises the essential feature of the invention is shown in what is now believed to be its preferred

form which comprises a casing 15 having one end reduced and externally threaded as indicated at 16 to engage an internally threaded opening in the manifold 12. The outer enlarged end of the casing 15 is preferably recessed at 17 to provide a valve seat 18 which partially closes the outer end of the casing and which is provided adjacent its periphery with an arcuate air inlet opening 19. Extending centrally through the valve seat 18 and longitudinally of the casing is a bolt or screw 20 secured in adjusted positions by means of a jam nut 21 engaging the inner face of the valve seat and concentrically mounted upon this bolt and engaging the seat 18 within the recess 17 is a disk valve 22 having an arcuate opening 23 adjacent its periphery adapted to register with the opening 19 when the valve is automatically adjusted in a manner to presently appear.

It is desirable, under certain atmospheric conditions, to vary the amount of air passing through the opening 23 in the valve 22 and for this purpose use is preferably made of a shutter or plate 24 engageable with the outer surface of the valve 22 and having one end thereof curved as indicated at 25 to conform to the curvature of the opening or slot 23. The shutter is also provided with an elongated slot 26 through which extends a screw 27 engaging the valve 22 whereby to hold the shutter in its adjusted positions. This shutter is manually adjusted toward and away from the opening 23 so as to vary the size thereof in conformity with the existing atmospheric conditions.

An operating lever 28 is pivoted intermediate its ends upon the bolt 20 and engages the outer face of the shutter 24, the end of the lever adjacent said bolt being connected to the valve 22 by means of a pin or rivet 29 secured therein so that when the lever 28 is adjusted about its pivot the valve 22 will be rotated and the opening 23 will be adjusted into and out of registration with the opening 19 and vary the size of said opening in accordance with the amount of adjustment of said valve. In order that the valve 22 may be retained in its adjusted positions the outer end of the bolt 20 has a spring 30 coiled thereabout which normally exerts an inward pressure upon the lever 28, shutter 24 and consequently the valve 22 thus causing the latter to frictionally engage the valve seat 18.

It is proposed to control the adjustment of the valve 22 by that of the rod 14 so that when the latter is actuated to adjust the throttle valve of the carburetor the auxiliary air valve will likewise be adjusted. For this purpose, use is preferably made of a supporting arm 31 having one end bent upon itself to provide a clamp 32 for receiving the rod 14 and said arm is secured to said rod by means of a small bolt 33 having a wing nut 34 threaded thereon and engageable with the adjacent end of the clamp 32. The other end of the arm 31 is connected, by a link 35 to the end of the lever 28 opposite 15 to that secured to the valve 22 and through this construction it will be apparent that when the rod 14 is shifted the lever 28 will be swung about its pivot and automatically adjust the disk valve 22 to regulate the 20 amount of air passing through the opening 19 into the casing 15 and from thence into the intake manifold.

What is claimed is:

An auxiliary air intake for internal com-

bustion engines comprising a casing adapted to have one end mounted in the intake manifold and having its other end recessed to provide a valve seat having an opening therein, a valve rotatably mounted in said recess and engaging said seat and having an opening adjustable into and out of registration with the opening in said seat, a pivot on which said valve is rotatable, a shutter element engaging the outer face of said valve and having an elongated slot therein for receiving said pivot, said shutter element being adjustable to vary the size of the opening in said valve, and means also extending through said slot and engaging said shutter element for retaining the same in adjusted 40 positions.

In testimony whereof, I affix my signature in the presence of two witnesses.

MARTIN R. SCHAFFER.
